John C. Lund

INVENTOR

BY Victor J. Evans

TORNEY

UNITED STATES PATENT OFFICE.

JOHN C. LUND, OF ASTORIA, NEW YORK.

DISPLAY RACK.

Application filed May 5, 1924. Serial No. 711,233.

To all whom it may concern:

Be it known that I, JOHN C. LUND, a citizen of the United States, residing at Astoria, Long Island, in the county of Queens 5 and State of New York, have invented new and useful Improvements in Display Racks, of which the following is a specification.

This invention relates to display racks and is an improvement over Letters-Patent 10 #1,013,032, granted to me on December 26th, 1911.

The principal object of the invention is the provision of a display rack which is collapsible to permit the same to be taken 15 down when not in use thereby taking up a minimum amount of space for storing purposes.

Another object of the invention resides in the construction of a display rack which includes a supporting structure. A collapsible shelf structure capable of adapting itself to the supporting structure for forming a plurality of steps, and whereby the shelf structure is held in position on the supporting structure by a tension means, and which tension means also serves to hold the shelf structure in a collapsed condition.

A still further object is to provide a rigid display rack which may be quickly assembled 30 or collapsed.

With these and other objects in view, the invention resides in certain novel construction and combination and arrangement of parts, the essential features of which are 35 hereinafter fully described, are particularly pointed out in the appended claims, and are illustrated in the accompanying drawing, in which:—

Figure 1 is a perspective view of the invention set up for use.

Figure 2 is a vertical sectional view on the line 2—2 of Figure 1.

Figure 3 is a perspective view of the shelf structure collapsed.

Figure 4 is a perspective view of a pair of extension plates which may be added to the structure shown in Figure 1 should additional shelving be desired.

Figure 5 is a side elevation of the plates 50 in use.

Referring more particularly to the drawing, the reference numeral 10 designates my display rack in its entirety, which includes a supporting structure 11 and a co-acting shelf structure 12. The supporting struc-

ture 11 in the present instance comprises a pair of identical end plates 13 which are arranged in spaced relation to each other and which are held in a set-up or vertical position by means of pivoted members 14 carried by the underside of the plates. When not in use, the members 14 may be moved to a position parallel to the length of the underside of the plates, but when in use, the same are adapted to be moved at right angle thereto. The plates 13 are formed with vertical walls 15 and horizontal walls 16 which are so provided as to form steps 17 on which the shelf structure is supported.

The shelf structure 12 comprises a plurality of identical slats 18, the end slats being provided with longitudinal grooves 19 for a purpose to be presently explained. Each slat 18 adjacent its ends is provided with openings 20, the walls of the openings at the ends thereof are provided with eyelets 21 to give the shelf structure a finished appearance. Passing through the openings 20 are a pair of flexible cables 22, one cable passing through the openings at one end of the slats and the other cable passing through the openings at the opposite end. The ends of the cables terminate short of each other after passing through the end slats and the ends of one cable are connected to the ends of the other cable by tension means or contractile springs 23. The springs 23 are adapted to rest in the grooves 19 of the end slats so as to lie flush with the top surface thereof. It will be seen that the shelf structure may be adjusted to a position by reason of its flexibility to permit the slats to co-act with the vertical walls 15 and the horizontal walls 16 and when in such position, the springs 90 are of such a tension as to hold the cables in a taut condition when the shelf structure is in a set-up condition. When the shelf structure is in the collapsed or folded condition as shown in Figure 3, the springs 95 will hold the slats one over the other in stack formation.

From the foregoing description, it will be seen that I have provided a collapsible structure which may be set-up or taken down in quick order and when set-up, the same will provide a rigid structure for use in displaying merchandise.

In Figures 4 and 5, I have shown a pair 110 of extension plates 24, which are provided

with pins 25 for insertion in recesses 26 in the plates 13 whereby additional shelf space may be provided should the same be required. The step surfaces of the plates 24 5 may be of the same width as those of the plates 13 or they may be of a larger width and in such case, a larger shelf structure will be necessary as shown in Figure 5.

While I have described what I deem to 10 be the most desirable embodiment of my invention, it is obvious that many of the details may be varied without in any way departing from the spirit of my invention, and I therefore do not limit myself to the 15 exact details of construction herein set forth nor to anything less than the whole of my invention limited only by the appended claims.

What is claimed as new is:—

- 20 1. A display rack comprising a pair of spaced supports having horizontal and vertical portions, members pivotally mounted on the underside of said supports for holding the same in a set-up position, the said 25 members adapted to be moved parallel with the underface of said supports when not in use, a plurality of slats connected together by flexible cables passing through open-

ings adjacent the ends of the slats, said slats being received in the horizontal and 30 vertical portions of said supports, and contractile springs connecting the ends of the cables for setting up a tension on opposite ends of the cables.

2. A display rack comprising a pair of 35 spaced supports having horizontal and vertical portions, a plurality of slats connected together by flexible cables passing through openings adjacent the ends of the slats, said slats being received in the horizontal and 40 vertical portions of said supports, and contractile springs connecting the ends of the cables for setting up a tension on opposite ends of the cables.

3. A collapsible shelving comprising a 45 plurality of slats having openings provided therein adjacent the ends thereof, cables passing respectively through the openings, and contractile springs respectively connected to the adjacent ends of the cables 50 and respectively seated in grooves provided in the end slats.

In testimony whereof I have affixed my signature.

JOHN C. LUND.
